SEPARABLE BROOCH OR THE LIKE

Adolph Katz, Providence, R. I., assignor to Coro, Inc.,
New York, N. Y., a corporation of New York

Application September 30, 1955, Serial No. 38,166

Term of patent 7 years

(Cl. D45—19)

Fig. 1

Fig. 3

Fig. 1 is a plan view of a separable brooch or the like showing my new design.

Fig. 2 is an edge view thereof.

Fig. 3 is a plan view illustrating the brooch in separate position.

I claim:

The ornamental design for a separable brooch or the like, substantially as shown.
